UNITED STATES PATENT OFFICE.

AUGUST G. SANDMAN, OF BALTIMORE, MARYLAND, ASSIGNOR TO WALTER P. MURPHY, OF CHICAGO, ILLINOIS.

FREIGHT-CAR.

1,349,106.

Specification of Letters Patent. Patented Aug. 10, 1920.

Application filed May 22, 1916. Serial No. 99,022.

To all whom it may concern:

Be it known that I, AUGUST G. SANDMAN, a citizen of the United States, residing at Baltimore, and State of Maryland, have invented certain new and useful Improvements in Freight-Cars, of which the following is a specification.

My invention relates to railway cars, particularly box cars the superstructures of which are of wood construction; and one of the principal objects of the invention is to provide an improved form of metal reinforcement for the end wall of a box car whereby the end of the car will be effectually strengthened at a minimum cost and increase in weight as against cargo thrusts, weaving stresses and other shocks, loads and pressures to which the end of a box car is peculiarly subjected when in service.

20 A further object of the invention is to provide a metal reinforcement for the end of a freight car which may be readily applied to old cars when brought in for repairs as well as to new cars in process of construction.

25 The invention consists in the novel and improved constructions, arrangements and devices to be hereinafter described and claimed for carrying out the above stated objects and such other objects as will appear from the following specification.

The invention is illustrated, in certain preferred embodiments, in the accompanying drawings wherein—

30 Figure 1 is a view, in elevation of the end of the superstructure of a railway box car fitted with the reinforcing means provided by my invention.

35 Fig. 2 is a sectional plan taken on line 2—2 of Fig. 1.

40 Fig. 3 is a sectional plan on line 3—3 of Fig. 1.

Fig. 4 is a vertical sectional view on line 4—4 of Fig. 1.

45 Fig. 5 is a view, in perspective, of one of the angle pieces for anchoring the inner or metal sheathing of the car wall to the framing of the car.

Fig. 6 is a view, in perspective, of the

inner brace member forming a part of the 50 reinforcing means.

Fig. 7 is a vertical sectional view illustrating a modification.

Fig. 8 is a fragmentary sectional plan on line 8—8 of Fig. 7, and

55 Fig. 9 is one of the angular members forming part of the reinforcing means used at the belt rails.

Like characters of reference designate like parts in the several figures of the drawings.

60 In Figs. 1 to 7 inclusive, I have shown the superstructure of a box car of ordinary wood construction. 25, 25 designate the corner posts, 26 the end plate, 27 the end sill, 28 the outer sheathing, 29 the end belt rail, 30, 30 65 the side belt rails, and 31, 31 the end posts.

It is well known that the end of a railway 70 box car is subjected to very severe thrusts and pressures due to the inertia of the superstructure of the car, when the train stops and starts, to the tendency of the cargoes to shift, and to other causes. It frequently happens that the end sheathing boards are broken out and even the end posts are often broken or torn from their attachments. To 75

strengthen and rigidify the end wall so as to prevent, as far as possible, such injuries to the car, I provide a metal reinforcement for the end wall of the car composed preferably as follows: 32, 32 are pressed steel 80

reinforcing members on the outside of the outer sheathing 28, preferably in line with and bolted to the end posts 31. These 85

reinforcing members, in order to give them added strength and rigidity, are formed with longitudinal corrugations 33, and as the stresses due to cargo thrusts are much greater against the lower part of the car wall the corrugations are made deeper in the upper half of the end structure than in the 90

Fig. 4. The corrugations 33 terminate within the ends of the reinforcing members 32, leaving flanges 34 which are bolted through the end plate 26 to a brace 35 which lies within the car. The middle portion of 95 the brace 35 lies against the inner surface of the end plate. It is bent at 37, 37 and again at 38, 38 so that it forms an arch, the ex-

tremities 39 of which are attached to the side plates 40 of the car. The brace is preferably an angle bar. It serves not only to give firm anchorage to the upper ends of the vertical reinforcing members 32 but also to stiffen and strengthen the upper portion of the end of the car as against weaving stresses.

The lower ends of the vertical reinforcing members 32 are secured to the under frame of the car in any suitable manner. Preferably they are anchored thereto by truss rods 41 which may run the length of the car. Instead of providing the car with the usual end lining I prefer to employ a metal inner sheathing which, besides being better calculated to take the thrust of the cargo, operates also to stiffen and strengthen the end so as to prevent the racking strains due to weaving. I have shown this inner sheathing as extending substantially from top to bottom of the end, although this is not essential. In the arrangement shown it consists of an upper plate 42 and a lower plate 43 each formed with horizontally extending corrugations 44 which merge into the plates within the side margins thereof, leaving flat flanges for attachment, as, for example, by bolts 45 to the end posts 25. The plates 42, 43 are overlapped at their meeting edges and at this point are preferably anchored to the side belt rails 30 by angular members 46. The upper end of the upper sheet 42 may intervene between the end plate 26 and the brace 35. The overlapping of the plates at the center strengthens the end belt rail 29, the plates being attached to the belt rail as, for example, by bolts 47. The car is further strengthened by the angular attaching members 46 which act to transmit any stresses on the end belt rail to the longitudinal side belt rails 30. The brace 35 reinforces the upper end of the end wall, that is, the end plate, and the vertical reinforcing members 32, which are anchored at the top to the brace and at the bottom are attached to the under frame of the car by the truss rods, serve to add strength to the end posts; all of the reinforcing members being united so that a distribution of stresses results. Preferably I employ cap pieces 48 for the lower ends of the reinforcing members 32, the truss rods 41 extending through these cap pieces. The extremities 39 of the brace 35 may be given an upward slant as shown in Figs. 4 and 6 so as to insure a better anchorage to the side plates. If desired the outer wood sheathing 28 might be omitted, in which case the lower edge of the inner sheathing plate 43 would be flanged down from the floor of the car.

A modified arrangement is shown in Figs. 7 to 9 inclusive. In this construction a wooden lining or inner sheathing is em-

ployed instead of the corrugated sheet metal sheathing previously described. In other respects the construction may be the same as that shown in the preceding figures. 49 is an upper lining and 50 a lower lining. 70 51 is a Z-bar which makes a grain-proof connection between the upper and lower linings and also serves to strengthen the car at the belt rail. In addition to this reinforcement I provide a channel shaped reinforcement 52 75 bolted to the end belt rail 53. The reinforcing member 52 is anchored to the side belt rails 54 by metal strips 55 each formed with three angularly projecting tongues. The middle tongue 56 enters and is riveted to the channel of the reinforcing member 52. The tongues 57 are riveted to the flanges 58 of the member on opposite sides of the channel.

Other modifications might be made without departure from the principles of my invention.

I claim:

1. In a railway box car, the combination with the end framing and sheathing of the car, of means for reinforcing the end of the car comprising a pair of substantially upright reinforcing members on the outside of the car having their lower ends anchored to the ends of the truss rods of the car, and a metal brace on the inside of the car to which the upper ends of said reinforcing members are secured; said brace being formed from a metal strip bent so that the middle portion thereof lies parallel to the plane of the end wall and the ends extend diagonally to the side walls of the car and are attached thereto.

2. In a railway box car, the combination with the end framing and sheathing of the car, of means for reinforcing the end of the car comprising a pair of substantially upright reinforcing members on the outside of the car, truss rods extending longitudinally of the car for anchoring the lower ends of the reinforcing members to the under frame of the car, and an integral angular metal brace on the inside of the car to which the upper ends of said reinforcing members are secured; said brace being bent so that its ends extend diagonally to the side walls of the car.

3. In a railway box car, the combination with the end framing and sheathing of the car, of means for reinforcing the end of the car comprising a pair of substantially upright reinforcing members on the outside of the car, truss rods extending longitudinally of the car for anchoring the lower ends of the reinforcing members to the under frame of the car, and an integral angular metal brace on the inside of the car to which the upper ends of said reinforcing members are secured, the middle portion of which brace lies parallel to the plane of the

end wall and the ends of which extend diagonally to the side walls of the car and are attached thereto.

4. In a railway box car, the combination 5 with the end framing of the car comprising corner posts and intermediate end posts, of a sheet metal sheathing secured to the inner sides of said corner and end posts and formed with a plurality of stiffening and 10 reinforcing corrugations, and a brace extending from side to side of the car and being connected to the upper end of said metal sheathing and to the side framing of the car.

15 5. In a railway box car, the combination with the end framing of the car comprising corner posts and intermediate end posts, of a sheet metal sheathing secured to the inner sides of said corner and end posts and 20 formed with a plurality of stiffening and reinforcing corrugations which terminate within the edges of the sheathing, and a brace extending from side to side of the car and being connected to the upper end 25 of said metal sheathing and to the side framing of the car.

6. In a railway box car, the combination with the end framing of the car comprising corner posts and intermediate end posts, of 30 a sheet metal sheathing secured to the inner sides of said corner and end posts and formed with a plurality of horizontal stiffening and reinforcing corrugations, and metal reinforcing members on the outside of and 35 secured to said end posts and extending at right angles to the reinforcing corrugations of said metal sheathing.

7. In a railway box car, the combination 40 with the end framing of the car comprising corner posts and intermediate end posts, of a sheet metal sheathing secured to the inner sides of said corner and end posts and formed with a plurality of stiffening and 45 reinforcing corrugations, and a bracing member, the center portion of which is secured to the upper end frame member of the car and to said metal sheathing and the ends of which extend diagonally across the car and are attached to the side walls 50 thereof.

55 8. In a railway box car, the combination with the framing of the car comprising corner posts and side belt rails, of a sheet metal sheathing secured to the inner sides of said corner posts and consisting of corrugated metal plates overlapped at said belt rails, and gussets for anchoring the overlapped portions of said plates to the belt rails.

60 9. In a railway box car, the combination with the framing of the car comprising corner posts and side and end belt rails, of a sheet metal sheathing secured to the inner sides of said corner posts and consisting 65 of corrugated metal plates overlapped

at said belt rails, and gussets for securing the overlapped portions of said plates to the end and side belt rails.

10. In a railway box car, the combination 70 with the end framing of the car comprising corner posts and intermediate end posts, of a sheet metal sheathing on the inside of said posts formed with horizontal corrugations which terminate within the edges of the sheathing so as to leave attaching 75 flanges for attachment to the corner posts, and means for securing said sheathing to the corner posts.

11. In a railway box car, the combination 80 with the end framing of the car comprising corner posts and intermediate end posts, of a sheet metal sheathing within said posts and secured to the same, said sheathing being formed with horizontally extending corrugations, and vertical reinforcing members 85 secured to said end posts and to the end plate and end sill of the car.

12. In a railway box car, the combination with the end framing of the car comprising corner posts and intermediate end posts, of 90 a sheet metal sheathing within said posts and secured to the same, said sheathing being formed with horizontally extending corrugations, and reinforcing members in alignment with and secured to said end posts and 95 provided with longitudinal corrugations.

13. An end reinforcement for a railway box car comprising a corrugated sheet metal sheathing arranged within and secured to the end framing of the car, a substantially 100 horizontal arched brace within the upper part of the end of the car to which the sheathing is secured, and a pair of substantially upright reinforcing members on the outside of the car, the upper ends of which 105 are secured to said brace and the lower ends to the under frame of the car.

14. An end reinforcement for a railway box car comprising a corrugated sheet metal sheathing arranged within and secured to 110 the end framing of the car, a substantially horizontal arched brace within the upper part of the end of the car to which the sheathing is secured, and a pair of substantially upright reinforcing members on the 115 outside of the car, the upper ends of which are secured to said brace and the lower ends to the under frame of the car, said reinforcing members being formed with outwardly pressed corrugations which decrease in depth 120 toward their upper ends and the sheathing with corrugations which run at right angles to the corrugations of the reinforcing members.

15. The combination with the side plates 125 and end framing of a railway box car, of a corrugated metal sheathing for the end of the car, and an integral angular brace, the middle portion of which is secured to the upper edge of said sheathing, the ends of 130

which extend diagonally across the car and are secured at their extremities to said side plates.

16. In a railway box car, the combination with the end plate and side plates of the car, of a corrugated sheet metal end sheathing secured to said end plate, and a brace, the middle portion of which extends parallel with and is secured to the upper edge of said metal sheathing and said end plate, the ends of which extend diagonally across the car and are anchored at their extremities to said side plates.

17. In a railway box car, the combination with the end framing and truss rods of the car, of a sheet metal sheathing having stiffening corrugations therein, means for reinforcing the end of the car comprising a substantially upright pressed steel member on the outside of the car, the lower end of which is anchored to the under frame by said truss rods, and a metal brace extending across the upper end of the car to which the upper ends of said reinforcing member and said sheathing are secured.

18. In a railway box car, the combination with the end framing and truss rods of the car, of a sheet metal sheathing having horizontal stiffening corrugations therein, means for reinforcing the end of the car comprising a pair of substantially upright reinforcing members on the outside of the car, the lower ends of which are secured to the under frame by said truss rods, and a metal brace on the inside of the car extending across the end and secured to the sides to which the upper ends of said reinforcing members and sheathing are secured.

19. In a railway car of wood construction, the combination with the side walls, of the car, of a composite end structure comprising a wooden sheathing and a metal sheathing element, the latter being formed with strengthening corrugations, a pair of vertical end braces arranged outside of the car and extending from top to bottom thereof, and a bracing structure within the car connected with said end braces and with the side plates at points remote from the end of the car.

20. In a railway car of wood construction, the combination with the side walls of the car, of a composite end structure comprising end posts, a wooden sheathing and a metal sheathing element, the latter being formed with strengthening corrugations, a pair of vertical end braces arranged outside of the car in alinement with said end posts and extending from top to bottom of the car, and a bracing structure within the car connected with said end braces and with the side plates at points remote from the end of the car.

21. In a railway car of wood construction, the combination with the side walls of the

car, of a composite end structure comprising end posts, a wooden sheathing, a metal sheathing element formed with strengthening corrugations, a pair of vertical end braces arranged outside of the car in alinement with said end posts and to which said metal sheathing and wooden end posts are secured, and a bracing structure within the car connected with said end braces and with the side plates at points remote from the end of the car.

22. In a railway car of wood construction, the combination with the side walls of the car, of a composite end structure comprising end posts, a wooden sheathing, a metal sheathing element formed with strengthening corrugations, a pair of vertical end braces arranged outside of the car in alinement with said end posts and to which said metal sheathing and wooden end posts are secured, a bracing structure within the car connected with said end braces and with the side plates at points remote from the end of the car, and truss rods extending lengthwise of the car which anchor the lower ends of the braces to the underframe of the car.

23. In a railway car of wood construction, the combination with the side plates, corner posts and end sills of the car, of a composite end structure comprising end posts, wooden sheathing, a metal sheathing element secured to the inner side of said end and corner posts and provided with horizontal corrugations which terminate within the edges of said element, a pair of metal braces on the outside of the car arranged in alinement with said end posts and provided with a reinforcing and strengthening corrugation which extends transversely to the corrugations of said metal sheathing element, means for securing said metal sheathing, end posts and end braces together, truss rods extending lengthwise of the car which anchor the lower ends of said metal braces to the end sill of the car, and a bracing structure within the car connected with said end braces and with the side plates comprising an angular metal strip bent to provide a flat portion which connects with the upper ends of said end braces and provides legs which extend diagonally from the end plate of the car to the side plates.

24. The combination with the underframe, end framing and side walls of a railway box car; of an end structure comprising a wooden sheathing, a sheet metal paneling united thereto, a pair of substantially upright reinforcing members on the outside of the end anchored at the bottom to the underframing, and a bracing structure within the car at the top having portions extending and attached to the side walls of the car, to the middle portion of which the upper ends of said reinforcing members are anchored.

25. In combination with the under-frame, end framing and sidewalls of a railway box car; of an end structure comprising a wood sheathing, a sheet metal paneling 5 united thereto having stiffening corrugations extending transversely to the wood sheathing, a pair of substantially upright reinforcing members on the outside of the

end anchored at the bottom to the under-framing and a bracing structure within 10 the car at the top having portions extending to and attached to the side walls of the car, to the middle portions of which the upper ends of said reinforcing members are anchored.

AUGUST G. SANDMAN.
